GARMENT OR IRONING PRESS

Philip N. Braun and Ernest Davis, Syracuse, N. Y.,
assignors to The Prosperity Company Inc.,
Syracuse, N. Y., a corporation of New York

Application April 20, 1929, Serial No. 356,797
Renewed October 17, 1936

37 Claims. (Cl. 192—131)

This invention relates to pressing machines as garment and laundry or ironing presses which have an opening and closing movement and in which there is liability of an operator being injured during the closing of the press especially where more than one operator is tending or arranging work on the machine or press.

An object of the invention is to devise a garment or ironing press having a movable member which is shiftable by the operator in order to close the press and requires the operator to step away from the press. The movable member may extend transversely of the press so that it pushes any other operator or operators away from the press when shifted.

Another object is to have the operator actuated means for operating the control means for the motor carried by the movable member.

Other objects appear throughout the specification.

The invention consists in the novel features and in the combinations and constructions hereinafter set forth and claimed.

In describing this invention, reference is had to the accompanying drawings in which like characters designate corresponding parts in all the views.

Figure 1 is a side elevation, parts being omitted, of a machine or press embodying this invention and with the press in open position.

Figure 2 is a front elevation of the press and the parts thereof seen in Figure 1, with some of the mechanism not pertinent to the invention being omitted.

Figure 3 is an enlarged fragmentary detail view, partly in section, of the movable member or guard bar and one of the manuals carried thereby for controlling the closing of the press.

Figure 4 is an enlarged fragmentary detail view partly in section, of a portion of the movable member showing the coacting coupling parts associated with the movable member or guard bar and contiguous parts of the shifting means therefor operated by the manual shown in Figure 3, the contiguous part of the companion motor control which is operated by the other coacting coupling part being also shown.

Figure 5 is a diagrammatic, fragmentary view of the motor means and the control valve means and release valve therefor. The motor control devices are shown in section.

Figure 6 is a view of the structure shown in Figure 4, but with the operating means for the motor control mechanism in coacting relation with each other when the guard bar has been

shifted to operated position away from the press so that the motor control means may be operated.

This machine comprises cooperating pressing elements or jaws, one of which is movable toward and from the other, operating mechanism for actuating the movable element or jaw including motor means, and a movable member or guard bar on the operator side of the machine normally arranged near the machine and which must be moved away from the press in order to close the same. The guard bar preferably extends the full dimension of the operator side of the machine.

As shown, the operator side of the machine is the front side only and the movable member or guard bar extends substantially the full width of the machine, that is, a distance equal to the length of the pressing elements, it being understood that the pressing elements are arranged with their long dimension transversely of the frame of the machine.

However, in some machines, one or two of the operators may stand at the end or ends of the pressing jaws, that is, either lateral side or both sides of the machine in which event, the bar would be shaped to guard the lateral sides as well as the front side.

The machine or press here illustrated comprises an upper pressing jaw, element or a head 1 movable toward and from the lower element 3 or buck 2 suitably mounted on a frame 3. The pressing elements or jaws are large in this type of machine and the press is usually tended by more than one operator.

The movable jaw 1 is actuated by operating mechanism which will now be described. The head 1 is carried by a yoke lever 4 pivoted at 5 between its ends to an upright 6 on the frame and is actuated by means connected to the rear arm of the yoke lever 4.

The motor means of the operating mechanism is fluid or pressure operated and in the illustrated embodiment of my invention, is operable with a two step operation. One step will preliminarily close the press head or bring the head 1 down close to the buck 2 and the second step will bring the head into final heavy pressing coaction with the buck 2. The press may be closed, if desired, with final heavy pressure in a one step operation.

The motor means here illustrated comprises two cylinders 7 and 8 and pistons therein operable successively to preliminarily close and finally close the press, or operable together to close the press in one operation. The cylinder 7 is

shown as mounted on the back leg 9 of the frame and as having its piston rod 10 connected to the rear arm of the yoke lever 4. The cylinder 8 is shown as located on the under side of the frame beneath the buck 2 and having the rod 11 of its piston 12 connected to motion transmitting means between the piston rod and the rear arm of the yoke lever 4. As here shown, the piston rod 11 is pivoted at 13 to the front 10 end of a link 14 connected at its rear end at 15 to the toggle consisting of links 16, 17, these links being pivoted together at 18. The link 16 is pivoted at 19 to the rear end of the yoke lever 4 and the link 17 is pivoted at 20 to the base of 15 the frame. The link 14 is here shown as pivoted to the link 17.

The link 14 is guided in its movement by a stationary cam slot 24, the link 14 having a follower 23 mounted on the link 14 at a point spaced from the pivot 13 connecting the piston rod 11 and the link. The upper part of the cam slot is inclined but slightly out of the horizontal so that the link acts as a lever somewhat during 25 the initial part of the closing movement of the press while the follower is moving along the horizontal or upper part of the slot. The lower part of the cam slot is inclined out of the vertical and when the follower 23 moves in the lower 30 part of the cam slot, the link 14 is pulled endwise, without any lever movement to straighten the toggle. The movement of the head into partially closed position by the piston and the cylinder 7 partly straightens the toggle and then 35 when motive fluid is permitted to enter the cylinder 8, the link 14 further straightens the toggle.

As the motor means is pressure operated, the controls therefor, that is, the means for controlling the flow of motive fluid to and from the same, are valves. The motors 7 and 8 are single acting and the press is opened by countersprings 21, 22 when the force or pressure on the piston 12 tending to hold it closed is released. The 45 control mechanism for controlling the operation of the motor means will now be described.

The casing 25 of the control valve for the cylinder 7 has a normally closed spring pressed intake valve 26 therein and a normally open exhaust valve 27 controlling an exhaust port 28. These valves 26 and 27 are connected together by a stem 29 so that they operate as a unit. The intake end of the casing 25 is connected by a pipe 30 to a source of supply of motive fluid, as compressed air, and a combined intake and exhaust pipe 31 leads from the casing 25 at a point between the valves to the intake port 32 of the cylinder 7. The valves are automatically locked in their operated positions preferably, by pressure 55 operated means as a diaphragm chamber 33 having a diaphragm 34 therein which acts upon a sliding stem 35 thrusting against one arm of a member 36 in the form of a lever pivoted at 37 to the valve casing and thrusting at 38 against the stem 39 of the exhaust valve 27. This lever 60 36 is one of the coacting coupling parts to be hereinafter referred to.

Obviously, upon depression of the lever 36, the exhaust valve 27 will be closed and the intake valve 26 opened so that air is free to pass from the feed line 30 through the valve casing 25, and pipe 31 to the cylinder 7 to actuate the piston therein to preliminarily close the press, and air also passes from the valve casing 25 through a duct 40, not previously referred to, to the pres-

sure side of the diaphragm chamber 33 to actuate the diaphragm 34 and lock the valves 26 and 27 in their operated position. The valves are released by exhausting the air from the diaphragm chamber as will be hereinafter described. 5

The flow of motive fluid to the cylinder 8 is controlled by a similar valve mechanism including a valve casing 41 having a normally closed spring pressed intake valve 42 therein, a normally open exhaust valve 43 controlling a port 10 44. These valves 42 and 43 are connected together by a stem 45 so that they operate as a unit. The intake end of the casing 41 is connected to a feed pipe 46 for compressed air and the casing is connected from a point between 15 the valves, by pipe 47, to a master valve mechanism 49 which is connected by the pipe 48 to the intake port 50 of the cylinder 8. The valves 42, 43 are actuated by a control member or coacting coupling part in the form of a lever 60 similar 20 to the lever 36 and pivoted at 61 between its ends so as to coact at 62 with the stem 63 of the exhaust valve 43.

The master valve mechanism 49 comprises a casing 51 having a normally closed spring pressed 25 intake valve 52 therein, and a normally open exhaust valve 53 controlling the outlet port 54. The valves 52 and 53 are connected together by a stem 55 so that they operate as a unit. The intake end of the valve casing 50 is connected 30 to a feed pipe 56 and the casing is connected at a point between the valves 52 and 53 to the pipe 48 previously referred to. The valves 52, 53 are operated by a diaphragm 57 in a diaphragm chamber 58, the pressure side of which is connected to the pipe 47. The diaphragm acts on the stem 59 of the exhaust valve 53.

The valves 42, 43 are locked in their operated position by a diaphragm chamber 64 having a diaphragm 65 therein acting on a sliding stem 40 66 which thrusts against one arm of the lever 60. The pressure side of the diaphragm chamber 64 is connected to a pipe 67 which in turn is connected to a pipe 68. The pipe 68 connects with a port in a casing 69 on the cylinder 8, the port 45 opening into the cylinder 8 in position to be uncovered by the piston 12 when the piston is at the end of its out or power stroke. Obviously, when the piston 12 has uncovered the port in the casing 69, air will pass back through the pipe 50 67 to the diaphragm chamber 64 and actuate the diaphragm 65 therein which in turn actuates the stem 66 and the lever 60 to hold the valves 42, 43 in their operated position.

The press is opened by exhausting the air from 55 the pressure side of the diaphragm chambers 64, 33 to permit the valves 42, 43 in the casing 41 and the valves 26, 27 in the casing 25 to return to their normal position. The return of the valves 42, 43 to their normal position, permits the air 60 to exhaust from the pressure side of the diaphragm chamber 58 through the pipe 47, valve casing 41 and exhaust port 44, and hence, permits the valves 52, 53 of the master valve to return to their normal position, so that the air 65 exhausts from the cylinder 8 back through the pipe 48, valve casing 51 and out through port 54. When the valves 26, 27 return to their normal position, the air therein exhausts from the cylinder 7 back through the pipe 31, valve casing 25 70 and out through exhaust port 28. Hence, when all valves are thus returned to their initial positions, the press is free to open under the influence of the springs 21, 22.

The air is permitted to exhaust from the dia- 75

phragm chambers 64, 33 by a trip or release lever 70 which when operated, opens two normally closed spring pressed exhaust or release valves 71 and 72 located in casings 73, 74 respectively, the casing 73 being connected by a pipe 75 to the pressure side of the diaphragm chamber 33 and the casing 74 being connected by a pipe 76 which is connected to the pipe 67, which pipe 67 as before stated, communicates with the pressure side of the diaphragm chamber 64. Thus when the release valves 71 and 72 are opened and the air permitted to exhaust from the diaphragm chambers, 33, 64, the valves 26, 27 and 42, 43 are free to return to their normal positions under the influence of return springs, not numbered, so that the exhaust passages 28 and 47 are open for the exhaust of air and when the exhaust valve 43 in the casing 41 opens, the air is free to exhaust from the pressure side of the diaphragm chamber 58 on the master valve 49 back through the pipe 47, valve casing 41 and out through exhaust port 44.

The trip or release lever 70 is common to both release valves 71, 72 and is here shown as mounted upon a rock shaft 77 having rock arms 78 and 79 thereon which press against the stems of the exhaust valves 71 and 72. When this release lever 70 is operated, obviously, the exhaust valves 71 and 72 will be opened. A momentary opening of these valves 71, 72 is all that is necessary to effect the return of the valves 26, 27; 42, 43 and hence, the valves 52, 53 to their initial positions.

The various valve mechanisms making up the control mechanism are suitably mounted on the frame of the machine. These valve mechanisms form no part of this invention per se and insofar as this invention is concerned, they are merely controls for a motor and as the motor is fluid operated, they are valves. For other types of motors such as electric motors, the controls would naturally be electric switches.

The operating member for controlling the actuation of the motor and forming the subject matter of this invention, comprises in the illustrated embodiment hereof, a movable member or guard bar 80 preferably extending transversely across the operator side of the machine, that is, in this embodiment of my invention, the front side. The guard bar is located about waist high and is normally adjacent to the press but is movable outwardly away from the machine or press to cause or require the operator to step away from the machine and also may be constructed to push away or require an additional operator or operators to step away from the machine.

The movable member or guard bar 80 controls the closing of the press in that so long as the movable member is in a position adjacent to the press, in which position the operator can approach the pressing jaws and lay work upon the buck, a part of the press mechanism is disconnected or displaced from operative relation with a coacting part of the press mechanism and the press cannot be operated. The press mechanism comprises the operating mechanism which closes the press, and as shown herein includes a motor means, and a control mechanism which controls the actuation of the operating mechanism which includes the operator actuated means, namely, the manuals 90 and 91 with their associated parts. One of these two mechanisms contains a disconnecting means which is in inoperative position when the movable member 80 is adjacent to the press and which is moved into operative position when the movable member 80 is moved to its

outward position away from the press. The press cannot be closed, therefore, until the movable member is in outward or forward position away from the press. The disconnecting means co-operates with a coacting coupling part and is moved from inoperative position in relation thereto into operative relation thereto or operative position upon outward movement of the movable member away from the press. 5

The disconnecting means is particularly shown in the control mechanism so that no part of the operating mechanism is actuated should the operator actuated or manual means 90 and 91 be operated when the movable member 80 is adjacent to the press. With the disconnecting means forming part of the control mechanism, the manual means 90 and 91 may be operated at will with the guard bar 80 in its position adjacent to the press without causing movement of an operating part. The disconnecting means may be included in or related to any part of the control mechanism, the primary purpose of the construction being that the motor means or operating mechanism be not operated upon actuation of the operator actuated means 90 and 91 so long as the movable member 80 is adjacent to the press. The above result may be obtained in numerous ways and is accomplished herein by the disconnecting means preventing the feeding of motive fluid to the motor means 7, 8 irrespective of the fact that the operator actuated means 90 and 91 have been actuated. 10

The guard or guard bar 80 is here illustrated as having an outward movement. The guard 80 is carried by upwardly extending swinging arms 81 and 82 which are pivoted at 83 at their lower ends to brackets 84, 85 at the base of the frame. These brackets carry housings 86, 87 into which the lower ends of the rock arms 81, 82 extend and in which are located the valve casings 25 and 41. 15 The swinging arms 81 and 82 give the guard bar 80 an outward swinging movement. 20

At the lower end of the rock arm 82 is carried a coupling part 89 for coacting with the coupling part or lever 36. The coupling part 89 is located below the pivotal point 83 of the arm 82 and is normally out of effective or operative relation with the coacting coupling part 36 and is movable into operative position therewith to operate said part when the bar 80 is swung to 25 its outer or safety position. 30

As the press here illustrated, has a two step operation, the coupling part 89 does not actuate the companion coupling part 36 when the guard bar 80 is moved to its outermost or safety position, but rather moves into a position in which the part 89 is over or in effective or operating relation to the coupling part 36 so that an additional operator or particularly a manual operator is required to actuate the coupling part 36. 35

The additional operator actuated or manually operated parts as here illustrated, comprise a handle 91 pivoted at 92 to the arm 82 under the bar 80. This lever 91 extends along the bar and is arranged so that it coacts with the bar 65 as a pinch handle. Lever 91 has an arm 93 extending into the adjacent arm 82 which is tubular and coacting with a head 94 at the upper end of a push rod 95 extending lengthwise of the tubular arm 82 and carrying a head or collar 70 96 at its lower end to which the coupling part 89 is secured. Gripping of the handle lever 91 toward the bar 80 causes the rod 95 to be moved downwardly and hence shifts the coupling part 99 downwardly so as to operate the companion 75

coupling part or lever 36 of the control means 25 for the motor.

A similar grip handle 90 corresponds to the grip handle 91 and operates similar mechanism 5 for controlling the operation of the lever 60 which controls the valves in the valve casing 41. Since these two mechanisms are similar it is thought to be sufficient if only one of the mechanisms is particularly described.

10 The downward movement of the rod 95 is against the action of a returning spring 97 located in the hollow arm 82. The coupling member 89 is pivotally mounted at 98 on the head or collar 96 and is acted upon by a spring 99 15 which normally holds it in the position shown in Figure 4. The coupling part 89 has a jack knife movement for the purpose hereinafter explained in connection with the operation of the machine. The devices described for operating 20 the control means or valve 25 are operator actuated or manual means.

In the particular disclosure herein, the disconnecting means, represented by the parts 88 and 89, is provided between the operator actuated means, which includes the manuals 90 and 91, and the control valves 25 and 41 or some part 25 of the control means operatively connected to the valves, such as the levers 36 and 60. In this particular construction the operator actuated 30 means or manual means, represented by the manuals 90 and 91 with the push rods 95 and their associated mechanism 88 and 89, are normally in inoperative position or relation with respect to the control means, or particularly the 35 levers 36 and 60. Obviously, in this particular form of construction the control valves are not operated so long as the movable member 81 is in its position adjacent to the press, even though the manuals 90 and 91 are operated. The operator 40 actuated means is, however, brought into operative relation with the control means 25 and 41 upon movement of the guard 80 to its position away from the press. In the preferred construction the manual means with the manuals 90 and 45 91 are carried by the guard bar, although this operator actuated means may be otherwise positioned, as desired. The purpose of the construction is that the operator actuated means be disconnected from the control means so long 50 as the guard 80 is in its position adjacent to the press.

The outward movement of the bar 80 is against the action of a suitable returning spring 100 and the bar is limited in its outward swinging movement by a stop or shoulder 101 carried at the rear end of a sliding rod 102 which rod is pivoted at its front end at 103 to the arm 81. There is a similar rod connected to arm 82. The rod 102 is guided in a pivoted tubular guide 60 104 pivoted at 105 to a bracket 106 on the front leg of the machine.

In operation, the operator after the work is laid on the buck 2 pulls the bar 80 outwardly from the full line position to the dotted line 65 position shown in Figure 1 and in so doing, must step away from the machine. Any other operator will be pushed away or given a warning by the bar 80 pushing against him, or in case the additional operator does not step back, the bar can 70 not be moved to its outermost position in which position the press cannot be closed. The movement of the bar to its outermost position brings the coupling part 89 in juxtaposition or operative relation to the coating coupling part 36.

75 For the two step operation, the operator grips

the lever 91 moving it toward the bar 80. This pushes the rod 95 downwardly and shifts the companion coupling part 88 downwardly into engagement with the end of the lever or coupling part 36 to open the intake valve 26 and close the 5 exhaust valve 27 thus permitting air to enter the cylinder 7 and preliminarily close the press. While the press is preliminarily closed, that is, while the head is close to the buck but slightly spaced apart therefrom, air blowing and steam 10 blowing and other analogous operations may be performed.

The operator then grips or operates the other handle 90 and moves the corresponding rod 95 downwardly and thereby moves the coupling part 15 89 into engagement with the companion coupling part or lever 60. The intake valve 42 is opened and the exhaust valve 43 is closed which permits air to enter the cylinder 8 as before described to actuate the piston therein to close the press under 20 heavy pressure. The valves lock as before explained in their operated position. To release the press, the operator operates the trip lever 70 as before explained. To close the press, the operator may grip both handles 90, 91 simultaneously and 25 effect the closing of the press in one step or the operator may grasp and operate the lever 90 before he pulls the bar 80 outwardly. In this event, the press does not close until the guard bar 80 is moved to its outward position at which time 30 the corresponding coupling part 88 will be pushed downwardly so that it will engage and operate the companion coupling part 36 when the bar 80 reaches its outer or safety position.

For a first step operation, the operator may 35 grasp and operate both grip levers 90 and 91 when the bar 80 is in its normal position so that when the bar is swung to its outer or safety position, both coupling parts 89 will operate the companion control parts 36, 60 upon the outward 40 movement of the safety bar 80. It will be observed, therefore, that the outward movement of the guard 80 with the actuators 89 depressed will operate the control valve or valves.

After the press is closed upon releasing of the 45 movable member or guard bar 80 or upon releasing of the holding force thereon, the spring 100 will return the bar to its normal position. The coupling parts 89 are free to yield or have an action analogous to a ratcheting action in the 50 event, the operator still grips the handles 90, 91 or maintains her hold on the bar 80 when it is returning to its normal position. Ordinarily, these coupling parts 89 move away from the companion coupling parts 36, 60 to clear them when 55 the handles 90 and 91 are released during the return movement of the bar 80 by the spring 100.

What we claim is:

1. A garment or ironing press comprising, cooperating pressing jaws, operating mechanism to 60 open and close the press, control mechanism controlling the actuation of the operating mechanism including, a movable member shiftable inwardly towards and outwardly away from the press a distance sufficient to require the operator to step 65 away therefrom, and operator actuated means for operating the control mechanism; and means included in one of the aforesaid mechanisms normally in inoperative position and connected with the movable member so that it is movable into 70 operative position upon the outward shifting thereof.

2. A garment or ironing press comprising cooperating pressing jaws, mechanism for opening and closing the press including motor 75

means, control means controlling the actuation of the motor means, a movable member mounted on the operator side of the press and movable towards and away from the press, operator actuated means carried by the movable member for actuating the control means to control the closing of the press upon outward movement of said movable member away from the press, locking means to hold the press closed, and additional means for controlling the opening of the press independently of said member.

3. A garment or ironing press comprising co-operating pressing jaws, mechanism for opening and closing the press including motor means, control means controlling the actuation of the motor means, a guard extending transversely of the front side of the press substantially the full dimension of the operator side of the press and movable toward and away therefrom, means carried by the guard for actuating the control means to control the closing of the press upon outward movement of said movable member, means to hold the press closed, and additional means for controlling the opening of the press.

4. A garment or ironing press comprising co-operating pressing jaws, operating mechanism for opening and closing the press, including motor means, a movable member mounted on the operator side of the press and movable toward and away from the press, control mechanism connected with the motor means to control the closing of the press comprising, two coacting coupling parts normally disconnected from operative relation with each other, one coacting coupling part being shiftable by said movable member into operative relation with the other when the member is moved away from the press, and one of said coacting coupling parts being operable by the operator.

5. A garment or ironing press comprising co-operating pressing jaws, operating mechanism for opening and closing the press including motor means, a movable member mounted on the operator side of the press and movable toward and away therefrom, control mechanism connected with the motor means to control the closing of the press including, two coupling parts normally disconnected from operative relation with each other, one coupling part being shiftable by said movable member into operative relation with the other coupling part when said movable member is shifted away from the press, and release means for the control mechanism operable independently of said movable member.

6. A garment or ironing press comprising co-operating pressing jaws, mechanism for opening and closing the press, including motor means, a movable member mounted on the operator side of the press and movable away from the press, control means for the motor means to control the closing of the press, two coacting coupling parts one being shiftable by said movable member into effective relation with the other when said member is moved away from the press, and a manual carried by said member and connected to the shiftable coupling part, the manual being operable after movement of the movable member away from the press to move the shiftable coupling part and actuate the other coacting coupling part when said parts are in coacting relation.

7. A garment or ironing press comprising co-operating pressing jaws, operating mechanism to open and close the press including motor means; control mechanism controlling the actuation of

the motor means including a motor control means, a movable member shiftable inwardly towards and outwardly away from the press a distance sufficient to require the operator to step away therefrom, operator actuated means for operating the motor control means, and means included in the operator actuated means and normally in inoperative position thereby being ineffective to operate the motor control means and connected with the movable member so that upon outward shifting of the latter the last-mentioned means is moved into operative relation thereby establishing operative relation with the control means.

8. A garment or ironing press comprising co-operating pressing jaws, operating mechanism to open and close the press including motor means, control means connected with the motor means, a movable member on the operator side of the press and being shiftable inwardly towards and outwardly away from the press a distance sufficient to require the operator to step away therefrom, and operator actuated means for operating the control means, the operator actuated means being normally disconnected from operative relation with the control means and one of these means being connected with the movable member whereby upon the outward shifting of the movable member the operator actuated means is operatively connected with the control means whereby the control means is operable by the operator actuated means.

9. A garment or ironing press comprising co-operating pressing jaws, operating mechanism to open and close the press including motor means, control means connected with the motor means, a movable member shiftable inwardly towards and outwardly away from the press a distance sufficient to require the operator to step away therefrom, and operator actuated means carried by the movable member for operating the control means, the operator actuated means being normally disconnected from operative relation with the control means whereby upon the outward shifting of the movable member the operator actuated means is operatively connected with the control means.

10. A garment or ironing press comprising co-operating pressing jaws, operating mechanism to open and close the press including motor means, control means connected with the motor means, a guard extending transversely of the press on the operator side thereof and shiftable inwardly towards and outwardly away from the press a distance sufficient to require the operator to step away therefrom, and operator actuated means for operating the control means, the operator actuated means being normally disconnected from operative relation with the control means and one of these means being connected with the guard whereby upon the outward shifting of the guard the operator actuated means is operatively connected with the control means.

11. A garment or ironing press comprising co-operating pressing jaws, operating mechanism to open and close the press including motor means, control means connected with the motor means, a guard extending transversely of the press on the operator side thereof and shiftable inwardly towards and outwardly away from the press a distance sufficient to require the operator to step away therefrom, and operator actuated means carried by the guard for operating the control means, the operator actuated means being normally disconnected from operative relation with

the control means whereby upon the outward shifting of the guard the operator actuated means is operatively connected with the control means whereby the control means is operable by the operator actuated means.

12. A garment or ironing press comprising, co-operating pressing jaws, operating mechanism to open and close the press including motor means, control means connected with the motor means, 10 a movable member on the operator side of the press, a hinge pivotally supporting the movable member at the lower end thereof for permitting swinging of the same inwardly towards and outwardly away from the press a distance sufficient 15 to require the operator to step away therefrom, and operator actuated means for operating the control means, the operator actuated means being normally disconnected from operative relation with the control means and being connected 20 with the movable member so that upon the outward swinging of the movable member the operator actuated means is operatively connected with the control means whereby the control means is operable by the operator actuated means.

13. A garment or ironing press comprising co-operating pressing jaws, operating mechanism to open and close the press including motor means, control means connected with the motor means, 30 a guard extending transversely of the press on the operator side thereof, a hinge pivotally supporting the guard at the lower end thereof for permitting swinging of the guard inwardly towards and outwardly away from the press a distance sufficient 35 to require the operator to step away therefrom, and operator actuated means for operating the control means, the operator actuated means being normally disconnected from operative relation with the control means 40 and one of these means being connected with the swinging guard so that upon the outward swinging of the guard the operator actuated means and the control means become operatively connected whereby the control means is operable by the operator actuated means.

14. A garment or ironing press comprising co-operating pressing jaws, operating mechanism to open and close the press including motor means, control means connected with the motor means, 50 a guard extending transversely of the press on the operator side thereof, a hinge pivotally supporting the guard at the lower end thereof for permitting swinging of the guard inwardly towards and outwardly away from the press a distance sufficient 55 to require the operator to step away therefrom, and operator actuated means carried by the guard for operating the control means, the operator actuated means being normally disconnected from operative relation with the control means whereby upon the outward swinging of the guard the operator actuated means is operatively connected with the control means whereby the control means is operable by the operator actuated means.

15. A garment or ironing press comprising co-operating pressing jaws, operating mechanism to open and close the press including motor means, control means connected with the motor means, 60 a movable member on the operator side of the press and being shiftable inwardly towards and outwardly away from the press a distance sufficient 65 to require the operator to step away therefrom, operator actuated means for operating the control means, the operator actuated means being normally disconnected from operative relation

with the control means and one of said means being connected with the movable member so that upon the outward shifting of the movable member the operator actuated means and the control means become operatively connected, locking means for holding the control means in operated position, and releasing means for the control means operable independently of the movable member, whereby the control means is operable by the operator actuated means.

16. A garment or ironing press comprising co-operating pressing jaws, operating mechanism to open and close the press including motor means, control means connected with the motor means, 15 a movable member on the operator side of the press and shiftable inwardly towards and outwardly away from the press a distance sufficient to require the operator to step away therefrom, operator actuated means for operating the control means including means therein normally disconnected from operative relation to the control means and connected with the movable member so that upon the outward shifting of the movable member the disconnected means is moved into operative relation whereby the control means is operable by the operator actuated means.

17. A garment or ironing press comprising co-operating pressing jaws, operating mechanism to open and close the press including motor means, control means connected with the motor means, a movable member shiftable inwardly towards and outwardly away from the press a distance sufficient to require the operator to step away therefrom, means returning the movable member to its initial position adjacent to the press 35 when released by the operator, operator actuated means for operating the control means including means therein normally disconnected from operative relation to the control means and connected with the movable member so that upon the outward shifting of the movable member the disconnected means is moved into operative relation whereby the control means is operable by the operator actuated means, locking means for holding the control means in operated position, and releasing means for the control means.

18. A garment or ironing press comprising co-operating pressing jaws, operating mechanism to open and close the press including motor means, control means connected with the motor means, a guard extending transversely of the press on the operator side thereof and shiftable inwardly towards and outwardly away from the press a distance sufficient to require the operator to step away therefrom, means returning the guard to its initial position adjacent to the press when released by the operator, operator actuated means for operating the control means including means therein normally disconnected from operative relation to the control means and connected with the movable member so that upon the outward shifting of the movable member the disconnected means is moved into operative relation whereby the control means is operable by the operator actuated means, locking means for holding the control means in operated position, and releasing means for the control means.

19. A garment or ironing press comprising co-operating pressing jaws, operating mechanism to open and close the press including motor means, 70 control means connected with the motor means, a guard extending transversely of the press on the operator side thereof, a hinge pivotally supporting the guard at the lower end thereof for permitting swinging of the guard inwardly towards

and outwardly away from the pressing jaws a distance sufficient to require the operator to step away therefrom, means returning the guard to its initial position adjacent to the press when released by the operator, operator actuated means for operating the control means including means therein normally disconnected from operative relation to the control means and connected with the guard so that upon the outward swinging of the movable guard the operator actuated means and the control means become operatively connected whereby the control means is operable by the operator actuated means, locking means for holding the control means in operated position, and releasing means for the control means.

20. A garment or ironing press comprising co-operating pressing jaws, operating mechanism to open and close the press including motor means, control means connected with the motor means, a movable member on the operator side of the press and shiftable inwardly towards and outwardly away from the press a distance sufficient to require the operator to step away therefrom, operator actuated means, and means rendering the operator actuated means effective to actuate the control means only upon the outward shifting of the movable member.

21. A garment or ironing press comprising co-operating pressing jaws, operating mechanism to open and close the press including motor means, control means connected with the motor means, a movable member on the operator side of the press and shiftable inwardly towards and outwardly away from the press a distance sufficient to require the operator to step away therefrom, operator actuated means carried by the movable member, and means connected with the movable member and ineffective to permit actuation of the control means by the operator actuated means until the movable member has been shifted outwardly.

22. A garment or ironing press comprising co-operating pressing jaws, mechanism for opening and closing the press including motor means, a movable member mounted on the operator side of the press and shiftable away therefrom, the movable member being shifted by the operator, control means for the motor means, a manual carried by the movable member to operate the control means, coacting coupling parts carried by said control means and the movable member respectively and normally out of coacting relation, the coupling part carried by the movable member being moved into operative relation with the other coupling part upon the outward shifting of the movable member, said manual being connected to the coupling part carried by the movable member and operable after the coupling parts are in operative relation to shift the same to actuate the other coupling part and the control means.

23. A garment or ironing press comprising co-operating pressing jaws, mechanism for opening and closing the press, including motor means, a guard located on the operator side of the press and extending substantially the full dimension of the operator side thereof and shiftable away therefrom, control means for the motor means, a coupling part connected with the control means, a coupling part shiftable by the guard into coacting relation with the aforesaid coupling part upon the outward movement of the guard, and a manual carried by the guard and connected to the shiftable coupling part, the manual being operable after outward shifting of the guard to

move the shiftable coupling part to actuate the first coupling part and the control means.

24. A garment or ironing press comprising co-operating pressing jaws, mechanism for opening and closing the press, including motor means, a guard bar located on the operator side of the press and extending substantially the full transverse dimension of the operator side thereof and shiftable away therefrom, control means for the motor means, a coupling part carried by the control means, a coupling part connected with and shiftable by the guard bar into coacting relation with the first coupling part upon the outward movement of the guard bar, and a manual carried by the guard bar and connected to the shiftable coupling part, the manual being operable after outward shifting of the guard bar to move the shiftable coupling part to actuate the first coupling part and the control means, said manual being in the form of a pinch handle lying along the guard bar.

25. A garment or ironing press comprising co-operating pressing jaws, mechanism for opening and closing the press, including motor means, a guard bar located on the operator side of the press and extending substantially the full dimension thereof and shiftable away therefrom, control means for the motor means, a first coupling part carried by the control means, a coupling part connected with and shiftable by the guard bar into coacting relation with the first coupling part upon the outward movement of the guard bar, a manual carried by the guard bar and connected to the shiftable coupling part, the manual being operable after outward shifting of the guard bar to move the shiftable coupling part and actuate the first coupling part and the control means, a spring for returning the guard bar when released by the operator to its initial position, locking means controlled by the closing of the press to hold the control means in its operated position, and release means for the control means to effect the opening of the press.

26. A garment or ironing press comprising co-operating pressing jaws, mechanism for opening and closing the press, including motor means, control means for the motor means, separate manuals for the control means operable to initiate a preliminary closing step and a full closing step of the press and both operable to initiate a full closing of the press in a one step operation, a guard bar on the operator side of the press and extending substantially the full dimension of the operator side, means supporting the guard bar for shifting movement away from the press, and means controlled by the guard bar for rendering the manuals operative to actuate the control means only when the guard bar is spaced from the press, said manuals being carried by the guard bar, and an enclosure surrounding the next aforesaid means so that the control means is operable only upon the outward shifting of the guard bar and operation of the manuals.

27. A garment or ironing press comprising co-operating pressing jaws, operating mechanism to open and close the press including motor means, control means connected with the motor means, a movable member on the operator side of the press and shiftable inwardly towards and outwardly away from the press a distance sufficient to require the operator to step away therefrom, means returning the movable member to its initial position adjacent to the press when released by the operator, operator actuated means for operating the control means, the operator actuated

- means being normally disconnected from operative relation with the control means and upon outward shifting of the movable member the operator actuated means is operatively connected 5 with the control means whereby the control means is operable by the operator actuated means, locking means for holding the press in operated position, and releasing means for the locking means.
10. 28. A garment or ironing press comprising co-operating pressing jaws, operating mechanism to open and close the press including motor means, control mechanism connected with the motor means, a movable member on the operator side of 15 the press and shiftable inwardly towards and outwardly away from the press a distance sufficient to require the operator to step away therefrom, operator actuated means for operating the control means, means connected with the movable member so as to render the operator actuated means effective only when the movable member 20 has been shifted outwardly, and an enclosure surrounding the next aforesaid means so that the mechanism is operable only upon outward shifting of the movable member and operation of the 25 control mechanism.
29. A garment pressing machine, comprising in combination, cooperative pressing elements; power operating mechanism therefor; means for 30 controlling the operation of the power operating mechanism including a pair of operator-operated controls both of which must be operated at the same time to initiate operation of the power operating mechanism to close the press; a movable member mounted in front of the pressing machine and movable near to and away from the pressing machine; means mounting the operator-operated controls on said movable member; and means connected with the movable member and 35 controlled thereby to render one of the operator-operated controls effective to cause operation of the power operating mechanism only when said movable member is in a position spaced from the pressing machine.
40. 30. A garment pressing machine, comprising in combination, cooperative pressing elements; power operating mechanism therefor; means for controlling the operation of the power operating mechanism including a pair of operator-operated controls both of which must be operated at the same time to initiate operation of the power operating mechanism to close the press; a guard including a rail mounted in front of the pressing machine on upright support members for movement of the rail toward and from the pressing machine; said operator-operated controls being mounted on the guard and one of said operator-operated controls including means by which it is ineffective to control the operating mechanism 45 except when the rail is in position away from the pressing machine.
45. 31. A garment pressing machine, comprising in combination, cooperative pressing elements; power operating mechanism therefor; means for controlling the operation of the power operating mechanism including a movable member mounted in front of the pressing machine and movable near to and away from the pressing machine; a pair of manual control devices mounted on the 50 movable member; and connections between the manual control devices and the power operating mechanism requiring movement of said movable member into a position away from the pressing machine and actuation of both manual control devices, when the movable member is in such 55 position, to initiate operation of the power mechanism to close the press.
32. A garment pressing machine comprising, cooperative pressing elements, power operating mechanism, therefor, a guard rail movably mounted on the operator side of the machine for movement close to and away from the machine, means for controlling the operation of the power mechanism including elements fixed from movement with the guard rail, a pair of operator-operated controls carried by the guard rail and movable relatively thereto, connections between the controls and said elements and operable upon movement of the guard rail into a position away from the machine to render the operator-operated controls carried by the guard rail operative to operate said elements and initiate the operation of the power mechanism, the operation of both of said controls being required to initiate the operation of the operating mechanism, said 60 connections being movable with the guard rail and shiftable thereby into position to coat with said elements, when the guard rail is shifted away from the machine and out of position to coat with said elements when the guard rail is shifted into a position close to the press.
33. In a garment pressing machine, in combination, cooperative pressing elements and operating mechanism therefor including fluid motor means to close the press under light pressure and 65 to apply heavy pressure to the pressing elements, means for controlling the supply of working fluid to the motor means for closing the press under light pressure including a first operator-operated member, means for controlling the supply of motive fluid to the motor means for closing the press under heavy pressure including a second operator-operated member and also a third operator-operated member, and means connected with the third operator-operated member and operated thereby in conjunction with one of the first and second operator-operated members to 70 control the flow of motive fluid to the motor means.
34. In a garment pressing machine, in combination, cooperative pressing elements; operating mechanism therefor including, a first motor for closing the press under light pressure, and a second motor for closing the press under heavy pressure; valve means for controlling the flow of motive fluid to the first motor, valve means for controlling the flow of motive fluid to the second motor, separate operator actuated means for operating each of said valve means, a common operator actuated member, connections between 75 said member and both of the operator actuated means so that operation of said common member and the separate operator actuated means moves both valve means to their positions assumed to permit the effective flow of motive fluid to the 80 motors.
35. In a garment pressing machine, in combination, cooperative pressing elements; operating mechanism therefor including, a first motor for closing the press under light pressure, and a second motor for closing the press under heavy pressure; valve means for controlling the flow of motive fluid to the first motor, valve means for controlling the flow of motive fluid to the second motor, manuals and connections operated thereby for each of said valve means, a member common to both manuals and the connections operated thereby and operable into one position to move the connections out of position to operate the valves and into another position to 85

move said connections into position to operate the valves when operated by the manuals.

36. In a garment pressing machine, in combination, cooperative pressing elements; operating mechanism therefor including, a first motor for closing the press under light pressure, and a second motor for closing the press under heavy pressure; valve means for controlling the flow of motive fluid to the first motor, valve means for controlling the flow of motive fluid to the second motor, manuals and connections operated thereby for each of said valve means, a member common to both manuals and the connections operated thereby and operable into one position to move the connections out of position to operate the valves and into another position to move said connections into position to operate the valves when operated by the manuals, and said common member being a guard movably mounted on the operator side of the machine.

37. A garment or ironing press comprising, cooperating pressing jaws one of which is movable towards and from the other; operating mechanism for actuating the movable jaw to open and close the press including, motor means; control means connected with the motor means, a movable member shiftable inwardly towards and outwardly away from the press a distance sufficient to require the operator to step away therefrom, a pair of operator actuated means for operating the control means and at least one of which is carried by the movable member, one of the operator actuated means being normally disconnected from operative relation with the control means and upon outward shifting of the movable member the operator actuated means is operatively connected with the control means. 5 10 15
